DASHPOT

Carroll D. Hobson, Goshen, Ind., assignor to Goshen Rubber Co., Inc., Goshen, Ind., a corporation of Indiana

Filed Jan. 12, 1959, Ser. No. 786,145
5 Claims. (Cl. 188—94)

This invention relates generally to dashpots and more particularly to dashpots whose principal operating parts are constructed from rubber or rubber-like material.

In the ordinary operation of an automobile, rapid braking allows the throttle to close quickly; and quick closing of the throttle is known to trap a gasoline-rich mixture of air in the intake manifold. This rich mixture frequently causes stalling of the engine.

Heretofore, stalling of automobile engines caused by trapping of these rich mixtures has been obviated by the incorporation of a metal dashpot with the carburetor throttle linkage. The dashpot delays closing of the throttle until the rich mixture has had an opportunity to be evacuated from the manifold.

Such metal dashpots are known to contain a rubber diaphragm; and although metal dashpots so constructed have proved useful, they have also presented a number of difficulties arising from the use of a considerable number of metal parts. In operation, certain parts slide against other parts and there is some tendency to sticking. Furthermore, these sliding parts are inclined to wear unevenly and shorten the overall life of the dashpot. Squeaking and other noises also develop in use.

These prior art dashpots also present complicated assembly requiring special tools and crimping devices. Furthermore, due to the metal construction, air escape orifices change in size with changes in temperature, thereby altering the performance of the unit. Additionally, breakage of any part of such a dashpot requires scrapping of the entire unit.

Therefore, a general object of the present invention is to provide an improved dashpot which overcomes the limitations of the prior art by having the principal operating parts made from rubber or rubber-like material.

Another object of the present invention is to provide a dashpot having no sliding parts.

Yet another object of the present invention is to provide a dashpot which is noiseless in operation.

A further object of the invention is to provide a dashpot of simple, economical construction and which is capable of hand assembly.

A still further object of the invention is to provide a dashpot whose performance is not subject to pronounced variations resulting from changes in temperature.

Additional objects and features of the invention pertain to the particular structure and arrangements whereby the above objects are attained.

The structure in accordance with the invention includes a substantially rigid base of hard rubber and a flexible, soft rubber, cup-like element which cooperates with the rigid base in defining a bellows chamber. This chamber is provided with a breather port and there is additionally included a bellows operating member.

The invention, both to its structure and mode of operation, will be better understood by the reference to the following disclosure and drawings forming a part thereof wherein:

FIG. 1 is the side view of an automotive carburetor having affixed thereto a dashpot according to the present invention;

FIG. 2 is a cross-sectional view of the dashpot shown in FIG. 1;

FIG. 3 is a cross-sectional view of the cup-like element of the dashpot according to the showing of FIG. 2;

2

FIG. 4 is a cross-sectional view of the base member for use with the cup-like member of FIG. 3; and

FIG. 5 is a perspective view of a mounting lug which may be molded as an insert in the base member shown in FIG. 4.

Referring now in detail to the drawings, specifically to FIG. 1, there is shown generally a dashpot 10 constructed in accordance with a preferred embodiment of the invention and affixed to an automotive carburetor 12. Since one illustrative use of dashpot 10 is obviously in the art of automotive internal combustion engines, herein-after such art will be used for purposes of explanation and illustration without limiting the applications and uses of the invention in any way.

Carburetor 12 is fastened to and communicates with the intake manifold 14 of a conventional gasoline engine. Furthermore, carburetor 12 is provided with an air inlet 16, a fuel line connection 18 and a throttle linkage 20. These elements are well known in the art and are constructed and arranged in conventional manner. Since these elements comprise no part of the present invention, they will not be described in detail. However, secured to the throttle linkage 20 is an extended arm 22 adapted to engage dashpot 10 for purposes which will be brought out hereinafter.

As best shown in FIG. 2, the dashpot 10 includes a cup-like element 24 which defines a bellows chamber 26. Since element 24 is necessarily flexible, it is preferably made from some suitable material, such as soft rubber. So fashioned, element 24 is able to take a position, such as the position shown by dotted outlines 28, wherein the volume of bellows chamber 26 is considerably reduced.

Element 24 is also provided with an operating post 30 which may contain a breather port 32, although it is recognized that port 32 may be provided separately from post 30. It should be noted that post 30 engages the headed end 34 of arm 22 across slot 36. Slot 36 thus provides the valve action necessary for proper operation of the dashpot 10, and it is recognized that this valve action may be equally well achieved by slotting the shoulder 38 of post 30.

The lower portion 24a of the cup-like element 24 is arranged to contain the base 40; and to that end, portion 24a is adapted to receive base 40 between the shoulder 42 and the lip 44. In order that base 40 may be secured in proper position, lip 44 may advantageously terminate in an upraised section 46, best shown in FIG. 3, which upraised portion may be engaged with the recess 48 provided in base 40.

Base 40 may conveniently be hollowed out to form a cavity 50 which cooperates to further define the bellows chamber 26. Additionally, base 40 may be provided with a mounting lug 52, by means of which dashpot 10 may be secured to a suitable bracket in some acceptable manner as by means of the lock nut arrangement 54.

Since the necessary rigidity and other characteristics required of base 40 may advantageously be provided by molding base 40 from hard rubber, lug 52 may be secured to base 40 as by being molded therein as an insert. To facilitate such molding, lug 52 may include a flange 55 having a number of perforations 56 arranged circumferentially thereabout.

For purposes of providing an easy understanding of the invention, it is advantageous to provide at this juncture a functional description of the mode of operation of the component parts. Assuming that the position of linkage 20 shown in FIG. 1 indicates an open position of the throttle, a sudden release of the accelerator mechanism, such as might be experienced upon braking, would result in a movement of linkage 20 in the general direction of arrow 60. Such movement would cause arm 22 to engage the post 30 of dashpot 10. Further move-

ment of arm 22, and therefore of linkage 20, would be determined by the rate at which air could escape from chamber 26 through the port 32 and the orifice formed by slot 36.

As the air escapes through slot 36, bellows chamber 26 will be reduced in volume and post 30 will be retracted into a position such as is indicated by dotted outlines 28, in which position element 24 is distorted from its original shape.

In such manner, the throttle associated with the linkage 20 would be allowed to close in somewhat gradual manner thereby allowing proper exhausting of the intake manifold 14.

Upon reapplication of force to the linkage 20, movement thereof in the general direction of arrow 62 would occur. Thereby, retraction of arm 22 would be experienced and dashpot 10 would, upon release of such distorting forces, reassume the form associated with the normal volume of chamber 26 according to the showings in solid outline in various figures. Air, naturally, would enter through the port 32 cooperating in this expansion of the chamber 26.

According to an important feature of the invention, the cup-like element 24 may be easily stretched by hand in order to effect rapid assembly to base 40. Element 24 may also be readily disassembled from base 40 by manual stretching. This feature of the invention permits quick assembly in manufacture and facilitates replacement of a torn or damaged part.

The above description has been given with specific regard to the use of the dashpot of the present invention with an automobile carburetor. However, this illustrative use should not be construed as limiting the invention to such an environment. It is realized that the invention is useful in the wide field generally served by dashpots, among which may be numbered door checks and a variety of timing devices.

Furthermore, the specific example herein shown and described is illustrative only. Various changes in structure will, no doubt, occur to those skilled in the art; and these changes are to be understood as forming a part of this invention insofar as they fall within the spirit and scope of the appended claims.

The invention is claimed as follows:

1. A dashpot comprising a substantially rigid base for attachment to a mounting structure, a flexible cup-like element of elastomeric material having an open end portion defined by a discrete peripheral wall flexibly fitting over and enclosing and engaging the peripheral surface of said base to be rigidified and closed thereby while permitting ready removal of the cup-like element and forming therewith a chamber with the remaining portion of the cup-like element forming a wall section collapsible independently of said peripheral wall and base, an operating post upstanding from said cup-like element remote from said base and adapted to receive a force

applicator for collapsing the collapsible wall section of the chamber, the spring constant of said elastomeric material being such as to return the collapsible wall section to its expanded condition upon removal of the force applicator, and a breather port communicating with said chamber and adapted to be partially restricted when the force applicator is applied to the operating post and adapted to be substantially unrestricted upon removal of the force applicator from engagement of the post.

2. A dashpot comprising a substantially rigid base for attachment to a mounting structure, a flexible cup-like element of elastomeric material having an open end portion defined by a discrete peripheral wall flexibly fitting over and enclosing and engaging the peripheral surface of said base to be rigidified and closed thereby and forming therewith a chamber with the remaining portion of the cup-like element forming a wall section collapsible independently of said peripheral wall and base, said peripheral wall including inwardly directed spaced flange means engaging opposite faces of said base to interlock the cup-like element with the base while permitting ready removal of the cup-like element, an operating post upstanding from the collapsible wall section of the cup-like element remote from said base and adapted to be engaged by a force applicator for collapsing the collapsible wall section of the chamber, the spring constant of the elastomeric material being such as to return the collapsible wall section to its expanded condition upon removal of the force applicator, and a breather port communicating with the chamber permitting ingress and egress of air during movement of the collapsible wall section under influence of a force applicator and upon its return to expanded condition.
3. A dashpot as claimed in claim 2, wherein the breather port extends axially through said operating post.
4. A dashpot as claimed in claim 2, wherein one of said flange means and the adjacent surface of said base being provided with mutually interlocking rib and groove means.
5. A dashpot as claimed in claim 5, wherein the base is formed of relatively hard rubber with a mounting structure molded therein, and wherein the cup-like element is formed of relatively soft rubber.
